UNITED STATES PATENT OFFICE.

FRED H. KINDL, OF CHICAGO, ILLINOIS, ASSIGNOR OF ONE-HALF TO
ROBERT BENNETT, OF SAME PLACE.

MACHINE FOR MAKING METAL STIRRUPS.

SPECIFICATION forming part of Letters Patent No. 379,202, dated March 6, 1888.

Application filed May 21, 1887. Serial No. 239,015. (No model.)

To all whom it may concern:

Be it known that I, FRED H. KINDL, a citizen of the United States, residing at Chicago, in the county of Cook and State of Illinois, 5 have invented certain new and useful Improvements in Machines for Forming Metal Stirrups, of which the following is a specification.

This invention relates to an improvement in machines for forming metal stirrups adapted 10 for use in the construction of buildings as loops or hangers for tying together certain timbers at their respective points of intersection.

The foregoing service of a metal stirrup has 15 required it to consist of a stout metal strap bent into proximately U shape, with each leg having a reverse bend at its terminal portion. The several bends necessary for such configuration are made rectangular, so as to conform 20 to the corners of the timbers that are to be held together. The legs of this stirrup are moreover twisted to an extent to bring their reversely-bent terminal portions into position to form at one end of the stirrup a sort of double- 25 pronged clasp, which may engage upon one timber, while another timber set at right angles to the former may fit in the rectangular half-loop at the opposite end of the stirrup.

The object of my invention, generally stated, 30 is to provide improved and simplified means for automatically forming such metal stirrups in a rapid and highly-efficient manner.

Certain objects, more particularly specified 35 in detail, are, to avoid the slow process of twisting by hand-manipulated appliances the legs of the hanger-blank bent into staple form, and to further avoid the liability of breakage or tearing of the blank, and the general complexity and inefficiency of action which would 40 be involved in an attempt to bend and twist the blank by a machine operating to act upon the principle of the hand-twisting operation. To such end I form the twists in the legs of the staple shaped blank by subjecting the blank 45 at certain points along its length to the action of dies, which serve to form the twists with certainty and great efficiency, avoid liability of breakage or tearing of the blanks, and generally simplify the construction of this portion of a machine for forming metal stirrups 50 such as described; also, to provide a simple

and efficient arrangement of devices for successively bending the metal strap into staple shape, holding the strap thus bent, and rolling the legs of the bent strap into twists; also, 55 to provide simplified and otherwise improved means for forming the reverse bends at the ends of the stirrup or hanger; to facilitate the removal of the completed hangers without detaching the former-block from the machine; 60 to provide certain improved features of construction serving to render the machine accurate and rapid in its action; to provide improved means for readily adapting the machine to the manufacture of hangers of different sizes; to provide for great strength and durability of mechanism combined with simplicity of structure, and to provide certain novel and improved details, all tending to increase the general efficiency of the machine. 65

To the attainment of the foregoing and other useful ends, my invention consists in matters hereinafter described, and particularly pointed out in the claims.

In the drawings, Figure 1 represents a top 75 plan view of a stirrup-forming machine involving the principles of my invention, and illustrates the position in the machine of the strap or bar and a reciprocatory former-block, A, preparatory to bending the strap or bar 80 upon such block. Fig. 2 represents in top plan substantially the portion of the machine shown to the left of the line 22 in the preceding figure, and illustrates the former-block A as having arrived at the limit of its stroke at 85 this end of the machine. Fig. 3 is a detail mainly representing in top plan view a device whereby one of the rollers for bending the strap upon the former A can be rendered self-adjusting. Fig. 4 is a section on the line 44, 90 Fig. 3. Fig. 5 represents a transverse vertical section taken on the line 55, Fig. 1, with the former-block intermediate of the ends of its stroke and at a point where the strap will be subject to the action of devices for giving 95 a quarter-twist to each of the two sides or legs of the stirrups. Fig. 6 is a detail sectional elevation representing in longitudinal vertical section a portion of the machine on the line 66 of Fig. 5. Fig. 7 represents an end view 100 of one of the two rollers adapted for service in twisting the sides or legs of the stirrup and

forming the claw-bends at one end of the same. Fig. 8 represents a finished metal stirrup. Fig. 9 represents in top plan view the greater portion of the machine to the right of line 5 2 2, Fig. 1, and shows the former-block advanced relatively to the first pair of bending-rollers to an extent sufficient to cause the strap to be bent around the end of the former-block. Fig. 10 represents a longitudinal vertical section on the line 10 10, Fig. 1. Fig. 11 is a view similar to Fig. 10, but represents the position of the several parts at the completion of the claw-bends at end of the stirrup.

In said drawings, B indicates a suitably-constructed frame or bed, which may be mounted upon any desired support and provided with ways and bearings appropriate for the several operative members of the machine.

The reciprocating former-block A is herein employed in conjunction with a couple of rollers, C, for bending the strap, so as to first bring it into a sort of rectangular U shape. To such end the rollers C are stationed at a point where the former-block may pass between them, and the former-block is made of a width corresponding to the desired space between the two sides or legs of the ultimately formed stirrup shown in Fig. 8, wherein d d represent the said two sides or legs of the stirrup.

30 The metal strap D, Fig. 1, is to be first placed and firmly held against one end of the block A, so that when the latter is advanced between the pressure-rollers C the strap will be bent around the two vertical corner edges and brought opposite the two vertical sides of the block, as in Fig. 9, the horizontal width or thickness of the block at said end serving to determine the length of the strap portion d' between the two rectangular bends d², and to thereby determine the width of the stirrup, which, of course, corresponds to the size of timber it is to receive.

The strap, when placed in position across the end of the block, as in Fig. 1, has a length 45 of its middle portion equal to the width of such block held against the latter by a suitable jaw or abutment, A', between which and the end of the block the strap will be firmly held, in order that it may be accurately bent around the two vertical corner edges of this end of the block.

The block A and the jaw or abutment A' are carried by a reciprocating table or slide-plate, A², which, while serving as a sliding base or vehicle for supporting and reciprocating the block or jaw, is also adapted for service as a "former," to be used in conjunction with devices, hereinafter described, for shaping certain portions of the stirrup.

60 As a means for giving to each side or leg d of the stirrup the partial twist shown at d³, Fig. 8, the sliding base plate or block A² is provided with a pair of lugs or raised projections, A³, which respectively lie at opposite sides of and set up to the block A when the latter is in position for bending the strap. These lugs or raised projections are each shaped

in conformity to the twist that is to be given to the flat strap or bar, and serve as male dies for operating in conjunction with corresponding female dies E, each formed by a suitably-shaped recess or concavity in one of a couple of rollers, E', that are set apart to an extent to permit the block, with the strap bent thereon, to pass between them, but to bring the female dies E down upon the male dies A³ at a moment proper for taking the two sides or legs of the partially-formed stirrup and rolling the same into the quarter-twists shown in Fig. 8.

The conjoint action of the dies A³ and E is illustrated in Fig. 5, wherein the two legs of the partially-formed stirrup are shown in cross-section between the dies.

The distance between the end of the block A, 85 against which the strap is to be held, and the end of the base A² (shown to the right in several of the figures) is such as to permit the end portions, d, of the strap to extend beyond such base after the strap has been bent, as in Fig. 9, and twisted, as in Fig. 8, in order to leave the end portions of the strap free to be bent to form the reverse bends d⁴. After the formation of the twists d³ by the dies, the lengths of strap between such points of twist and their 90 end portions that extend beyond the base will, by the action of the rolls E', be rolled down in a flat condition upon the base alongside the two vertical sides of the block A, after which the said projecting end portions of the strap 100 will be bent around the end of the base, as illustrated in Fig. 11, so as to form the claws or reverse bends d⁴ at one end of the stirrup. As a means for forming these rectangular 105 reverse bends d⁴, each roller, E', is provided with a radially-disposed jaw, E², adapted, when the said end of the base is below and substantially in vertical line with the axis of the roller, to clamp a free-end portion of the strap against both the vertical end face and 110 the bottom horizontal face of the base, as in said Fig. 11. From the foregoing it will be understood that the strap is to be first placed across the slide or reciprocating base, and for a certain length along its middle portion held firmly 115 against an end of the block A; that the two free lengths of the strap are then by means of suitable rollers bent inwardly or toward one another in order to form the two rectangular bends d² at one end of the stirrup and 120 thereby bring the strap into a proximately rectangular U or staple shape; that the two flat sides or legs of the staple-shaped strap are then rolled into quarter turns or twists d³, so as to bring one portion of each leg or side into a 125 plane at right angles to the plane of its remaining portion; and that the end or terminal portions of the strap are then forged or forced into the shape of the reverse bends d⁴ by certain dies or jaws, whereof the end of the base 130 A² affords at such time a stationary jaw for each of the two movable jaws E².

The block A is desirably made either movable upon or removable from the base A², the

feature of movability being mainly to permit the completed stirrup to be removed. In addition, however, to such feature, the block is preferably detachably held upon the base in order that blocks of different widths can be employed, it being understood that the width of the half-loop portion at one end of the stirrup is determined by the width or thickness of the block whereon the bends d^2 are formed.

As a simple and efficient way of holding the strap against one end of block A as long as may be necessary, and of permitting the introduction of the strap in the first instance into the machine, as well as the subsequent ready removal of the completed stirrup, the block A is herein hinged at one end to the abutment A', which may be fixed upon the the sliding base A². In this way the block A can be swung up, as indicated in dotted lines, Fig. 10, and the strap laid across the vertical face of the fixed jaw or abutment A', after which the block can be brought down into a horizontal position, as shown in full lines. The strap will then be practically clamped for a portion of its length between a pair of jaws, whereof the former-block provides a jaw upon which the bends d^2 are to be formed.

The block A can be held in position in any suitable way—as, for example, the base A² can be provided with one or more teeth, a, Fig. 10, which, when the block is lowered, will be received in corresponding notches in the block.

After the stirrup has been formed the block A can of course be moved from its position on the base by simply again swinging it up to an extent to free the completed stirrup. As a means for reciprocating the block A the sliding base A², whereon it is mounted, is arranged to reciprocate along suitable ways, b, on the bed B, and is provided with rack-bars F, which will preferably be adjustably secured to the reciprocating base A². These racks F are engaged by the feed or driving gears G, which, to render the machine compact and apply the power in an efficient manner, are arranged alongside the rolls E' and mounted so that both the rolls and the feed gears may revolve about a common axis. Under such arrangement the rolls E' and gears G should all be of about a uniform size or diameter in order to insure uniformity of action—that is to say, to cause the rolling action of the rolls to keep pace with the speed of the moving base A² during the advancement of the latter, and hence not only bring the die-faces A³ and E into proper cooperative relationship at the required moment, but also avoid any undue pull or tear of the strap during the operation of rolling it to form the twists d^3 . The rolls C are held at such distance apart that when the advancing block A passes between them their action upon the strap shall serve to force the free portions thereof around the vertical corners of the block, as illustrated in Fig. 9. Where the rolls C consist of straight cylindric rolls, it is necessary to provide means whereby they may stand back and out of the way of the raised die por-

tions A³ at times when such raised die portions pass the points where the rolls are stationed. To the attainment of such end the 70 rolls are mounted upon movable bearings H, which at proper moments are automatically shifted in directions lateral to the line of feed, so as to place the rolls C out of the way of the raised die portions A³.

Each movable bearing H consists of a suitably-formed slide-block, which is properly guided upon the main bed frame B, a convenient form of guideway being herein formed by a pair of raised guides, I, and a pair of raised 80 guides, I', with space between the two pairs for the operation of cam-slide K, arranged for shifting the block or bearing H. The cam-slide K works through a passage, h, Fig. 4, that is formed through the slide block or bearing H, and has its cam-face k maintained in opposition to a small roller, h', that is arranged within the passage through the block or bearing and desirably mounted in an adjustable bearing-piece, h''. These cam slides K may of course be operated in a variety of ways, but as a simple arrangement are actuated from the feed-gears G, to which end each gear is provided with an arm or finger, g, Fig. 6, arranged to engage in a notch, k', in the cam-slide. 95 These devices are so timed that at a proper moment during the advancement of the block A and base A² (which for some purposes may be regarded as a whole as a reciprocating former) the cam-slides will be drawn forward, so as to bring their low or narrower portions opposite the rollers h', and hence permit the bearings H to be pushed back and out of the way by the pressure of the advancing strap. Upon a return movement, however, of 105 the former the bearings H will be returned to their first positions by the action of the cam-slides.

It will be evident that while proximately conical or hemispherical rolls employed in place of the straight rolls C might serve to clear the raised die portions A³ without necessitating this automatic adjustment of the rolls, such arrangement would fail to properly finish the bends d^2 of the stirrup, and hence that 110 straight cylindric form of roll herein employed is desirable. After the two portions of the strap have been rolled into the twists d^3 the parts of the strap lying flat upon the base A² beyond the points of twist may be kept up to 120 the block A with their inner edges adjacent to the vertical sides of the block, either by the rolls C or by guides L, herein formed with or secured to the adjustable bearings H. In case these guides L are employed, their guiding-faces will lie parallel with the line of feed and about tangential to the rolls C, as shown in Fig. 3.

In order to readily loosen the bent ends d^4 of the strap or piece forming the stirrup from 130 the end of the base A² after the ends of the strap have been thus bent by the jaws E', the lower face of the base at such end is (when the base is at the end of its forward stroke) tem-

porarily formed by a flat plate or piece, a^3 , secured to the bed B and arranged to extend transversely across the same in position to nicely fit against the under side of the base 5 A² at the end of the forward stroke of the latter, as shown in Fig. 11. The terminals of the strap will therefore in reality be forced to lap under this piece a^3 , whereby when the base A is moved back the reverse bends will leave the 10 stationary piece a , and hence be left loose upon the end of the base. The result is, however, obviously the same as though the end portion of the base A² were temporarily increased to the required thickness by a piece or plate similar 15 to the piece a^3 , but removably or adjustably secured to the base A², and forced back from the end of such base at any time after the formation of the reverse bends d^4 of the stirrup. Hence, for the broader purposes of this 20 invention the reverse bends may be considered as formed upon the end of the base A², of which the plate a temporarily forms a part.

For different sizes of stirrups different sizes of block A can be employed, as hereinbefore 25 stated. In order to adjust the die portions A³ in position with reference to different sizes of blocks A, the top face of the base A² can be formed of one or more removable plates, a' , each provided with a raised die portion, A³, 30 as best shown in Fig. 5. These plates can be temporarily secured on the base A² by bolts, and while so applied may be considered as a part of the base. The rollers E' will of course be adjustably mounted, so that they can be set 35 with reference to the size of block A employed, to which end they are herein secured by bolts or screws e upon a rotary shaft, E³, which is desirably squared between its rounded ends or journals, so as to key both the gears G and the 40 rolls E' thereon without the necessity of splines or wedges. When the reciprocating base A² reaches the end of its forward stroke and has brought its end whereon the bends d^4 are formed directly under the rolls E', it is desirable that 45 the gears G should clear the racks F, so as to prevent further forward movement of the said base during the operation of forming these bends. To such end the racks are adjusted longitudinally upon the base A² in a manner 50 to permit the racks to leave the gears G at the proper moment. The reciprocating base A², however, abuts against a stop, M, at the end of its forward stroke, which said stop holds the base A² solid against the action of the jaws E'. 55 The stop is adjustably secured to the main bed-frame B, whereby, for different lengths of stirrups, it may be adjusted toward or away from the rollers, as may be found necessary.

In order to move the reciprocating base back 60 from its forward position to an extent to again bring the racks into engagement with the gears, the block A can be provided upon its top side with a lug or tooth, a^2 , adjustably secured to the block, and the rotary shaft E³ provided 65 with a radial lug or tooth, l, which is herein formed upon a collar, l', secured by a bolt or set-screw upon a rounded middle portion of

the said squared shaft E³. The object of the tooth on the shaft is to engage the tooth on the block A at the initial back movement of the 70 rotary shaft after the completion of the stirrup, whereby the slide A² will be moved back to an extent to bring the racks into engagement with the gears G. The collar l' is susceptible of rotary adjustment on the shaft, and 75 hence can be adjusted so as to set the tooth l with reference to any required adjustment of the tooth on the block A.

As a means for increasing the power of the machine, the rotary shaft E³, whereon the gears 80 G and rolls E' are secured, can be driven through the medium of certain gearing intermediate of the gears G and a power-driven rotary shaft, N, herein extended through the shaft E³, which is provided with an axial bore 85 for the reception of said shaft N. The rotary shaft N carries a couple of gears, P, one at each end of the shaft, which said gears are respectively connected with the next adjacent gears G by the intermediate gears, Q and R. 90 Thus, a small gear, P, secured on one end of shaft N, engages a larger gear, Q, secured on a short axle, S, to which is also secured a small gear, R, arranged to engage the gear G nearest said gear P, the gear P at the opposite end of the shaft being similarly connected with the other one of the two gears G.

The shaft N is herein shown provided with a crank-handle, but is of course understood to be driven in any desired way.

In operating this machine the metal bar or strap is preferably first properly heated and then placed in position which can be determined by an adjustable gage, D, and the machine then started up and the former advanced 100 until the work is completed.

It will be understood that in certain of the claims the term "former" comprehends substantially the base and the block, which as a whole constitute a former adapted to the ultimate shape of the stirrup, it being seen that the rollers, the upper die-faces, E, and the jaws serve to shape the strap upon such former.

What I claim as my invention is—

1. In a machine for forming metal stirrups such as described, male and female dies for forming the herein-described twists in the legs of the stirrups, substantially as set forth.

2. In a machine for forming metal stirrups substantially as described, the combination, 120 with the die-faces A³, raised upon a reciprocating base, of the rollers provided with corresponding depressed die-faces, E, for twisting the two sides or legs of the metal stirrup, substantially as described, and means for holding the work subject to the action of said die-faces during the movement of the reciprocating base.

3. In a machine for forming metal stirrups such as described, the jaws E², carried by oscillatory supports, combined with a former, whereon said jaws may bend the ends of a strap to form the reverse bends d^4 in the stirrup, substantially as described.

4. In a machine for forming metal stirrups such as described, a reciprocating former-block whereon the metal strap or blank can be bent into staple shape, rolls C, for bending 5 the metal strap into staple shape upon said reciprocating former-block during the passage of the latter between the rolls, and dies for rolling the legs of the staple-shaped strap into twists while such bent strap is held upon the former-block, said members being combined 10 and organized for operation, substantially as set forth.

5. In a machine for forming metal stirrups, the movable block A, combined with a reciprocating base provided with means for holding 15 the strap against an end of the block, rollers C, for bending the strap thus held against opposite sides of the block, the raised die-faces A³ at opposite sides of the block, and 20 rollers provided with corresponding depressed die-faces, E, for twisting the portions of the strap brought by the rollers C alongside the block, substantially as described.

6. In a machine for forming metal stirrups such as described, the combination, with a reciprocating base provided with raised die portions 25 A³, of means for holding upon such base and between said die portions a strap or bar bent to form the two angular bends d², and the 30 rollers provided with depressed die-faces E and with jaws E², said depressed die-faces in the rollers being adapted for co-operation with the die-faces on the reciprocating base, substantially as set forth.

35 7. In a machine for forming metal stirrups such as described, the block A, movably held upon a reciprocating base that is provided with raised die-faces A³, for the purpose set forth, in combination with the rollers C, mounted in 40 adjustable bearings, whereby the rollers may retreat when in opposition to the raised die-faces on the reciprocating base, substantially as described.

8. In a machine for forming metal stirrups 45 such as described, a roller, C, mounted upon a sliding block or bearing, in combination with a cam-slide for shifting said bearing in one direction, and a driving-wheel provided with an arm engaging the cam-slide, substantially as described.

50 9. In a machine for forming metal stirrups such as described, the reciprocating base provided with raised die faces A³, removably held upon said base, substantially as and for the purpose described.

55 10. In a machine for forming metal stirrups such as described, the former-block A, hinged at one end and arranged with its hinged end opposite an abutment, A', set to provide an

intervening space between the two, whereby 60 after a strap or blank has been bent into staple shape upon the block A the latter can be swung up to clear the strap without detachment of the block from the support to which it is attached, substantially as described. 65

11. In a machine for forming metal stirrups such as described, the reciprocating base provided with a jaw or abutment, A', combined with a block, A, hinged at one end to said abutment, but leaving between the abutment 70 and the hinged end of the jaw a space for receiving a metal strap or bar, substantially as and for the purpose described.

12. In a machine for forming metal stirrups such as described, a reciprocating base provided with a former-block combined with rolls 75 C, for bending a strap or blank into staple shape upon the former-block, means adapted for rolling the legs of the staple-shaped strap into twists, and comprising die-faces, respectively, on the reciprocating base, and a pair of rolls, between which said rolls the former-block passes during the reciprocation of said base, and gears G, engaging racks upon the reciprocating base, substantially as described. 80

13. In a machine for forming metal stirrups, such as described, the reciprocating former, substantially as described, provided with racks F, and in combination with the gears for engaging the racks, and the jaws E², mounted on 90 rotary supports, said members being organized whereby the jaws shall act to bend the ends of a strap upon the former after the racks are clear of the gears, substantially as described.

14. In a machine for forming metal stirrups 95 such as described, the reciprocating former, substantially as described, provided with racks F and a tooth, a², in combination with the gears G, for engaging the racks, and the tooth l, held upon a shaft, whereon said gears are 100 mounted and arranged for engaging the tooth a², in order to move the reciprocating former from its extreme forward position back to an extent to bring the racks into engagement with the gears, substantially as described. 105

15. In a machine for forming metal stirrups such as described, the combination, with a reciprocating former, substantially as set forth, provided with racks, of the gears G, engaging said racks, a gear, P, on a power-driven shaft 110 passing axially through a rotary shaft whereon the gears G are secured, and a set of gearing between the gears P and G, substantially as specified.
